SASH BALANCE

August Viehweger, Comstock Park, Mich., assignor to Grand Rapids Hardware Company, Grand Rapids, Mich., a corporation of Michigan

Application January 15, 1945, Serial No. 572,832

15 Claims. (Cl. 16—197)

1

This invention relates to improvements in sash balance.

The main objects of this invention are:

First, to provide a sash balance of the type embodying a tubular element having a spiral track in which the double element is provided with a tubular spiral track and one which may be economically produced and at the same time is very rigid and not likely to become sprung or to bind or clutchingly engage the torsion member when in use.

Second, to provide a sash balance of the type described in which the tubular element constitutes a lubricant retaining chamber so that the torsion spring and engaged parts may be effectively lubricated and squeaking and other noises practically eliminated.

Third, to provide a sash balance having these advantages in which the parts may be economically produced and assembled and easily mounted in operative relation to the sash of the window casing.

Fourth, to provide improved coacting tubular elements and torsion elements.

Objects pertaining to details and economies of the invention will definitely appear from the description to follow. The invention is defined in the claims.

A structure embodying the features of the invention is clearly illustrated in the accompanying drawing, in which:

Fig. 1 is a fragmentary elevation view of a window and casing with a sash balance embodying my invention installed therein, the balance being illustrated partially in longitudinal section.

Fig. 2 is a fragmentary sectional view corresponding to that of Fig. 1 with the sash in raised position.

Fig. 3 is an enlarged fragmentary view of the sash balance partially in longitudinal section on line 3—3 of Fig. 4.

Fig. 4 is a transverse section on line 4—4 of Figs. 1 and 3.

Fig. 5 is a fragmentary view looking from the right of Figs. 3 and 4 showing the details of the torsion element and its relation to the coacting tubular element.

Fig. 6 is an enlarged fragmentary longitudinal section on line 6—6 of Fig. 1.

Fig. 7 is a fragmentary view of a modified form or embodiment of the invention, the invention being mainly in the attaching bracket.

Fig. 8 is a perspective view of the attaching bracket of Fig. 7.

Fig. 9 is a fragmentary view corresponding to 55

2

that of Fig. 1 illustrating a modified form or embodiment of the invention in which the tubular member has a single spiral track as distinguished from the double track of Fig. 1.

5 Fig. 10 is an enlarged transverse section on line 10—10 of Fig. 8.

Fig. 11 is a perspective view of the torsion member of the embodiment shown in Figs. 9 and 10.

10 Fig. 12 is a fragmentary side elevation of a further modified form or embodiment of my invention provided with two spiral groove-like tracks.

Fig. 13 is an enlarged transverse section on line 13—13 of Fig. 12.

15 In the drawing 1 represents a window casing and 2 a window sash having a channel or groove 3 in the edge thereof adapted to receive the sash balance. In the embodiment of the invention illustrated in Figs. 1 to 6 the tubular element 20 designated generally by the numeral 4 is provided with two spiral groove-like tracks 5 and 6 of the same pitch so that they may both simultaneously coact with a torsion element having two track-engaging lugs or parts, these lugs or parts being oppositely disposed. This is of advantage in minimizing frictional and distortion stresses.

25 The tubular element comprises an inner member 7 and an outer member 8 closely embracing the inner member, the two members coacting to produce a very rigid tubular element and at the same time one which may be made of relatively light material and does not have the weight which would result from otherwise securing the same degree of rigidity or resistance to bending and deflecting stresses. Both of these inner and outer members are formed from strips 9 and 10 of ribbon stock, preferably steel, spirally coiled, and the convolutions or turns of the spirals are such that longitudinal slots 11 and 12 are formed by the edges of the strip or between the turns or convolutions of the spirally coiled strip.

30 The outer member is provided with a spiral corrugation 13 preferably centrally thereof, which forms a spiral groove 14. The spiral corrugation is positioned in the spiral slot 11 of the inner member as shown in Figs. 3 and 6. The slot 12 of the outer member is bottomed by the inner member and the parts coact to form the spiral groove or track 15.

35 A coiled torsion spring 16 is housed within the tubular member, being clutchingly engaged at one end with the inner end of the torsion rod 17 and at the other end engaged with the inner end of the anchoring rod 18, which is provided with

a pivoted attaching bracket 19, the anchoring rod having an ear 20 engaged by the pivot 21 carried by the bracket. The anchoring rod is provided with a bushing 22 secured to the anchoring rod at 23. These parts form a closure for one end of the tubular member.

The anchoring torsion rod 17 is disposed through a bushing 117 which is non-rotatively secured within the other end of the tubular member, the bushing in the embodiment illustrated having a hole 24 therein receiving the indentation 25 of the inner member, the outer member having a corresponding indentation 26. The members are thus secured against relative rotation as well as being secured to the bushing. The bushing is provided with ratchet teeth 27 at its inner end coacting with a ratchet head 28 mounted on the inner end of the torsion rod, this in the embodiment illustrated being in the form of a sleeve secured to the torsion rod by indenting at 29 into the recesses 30 formed in the torsion rod; see Fig. 3. The spring is under axial thrust and serves to urge the ratchet members into engagement. These parts provide an effective closure for this end of the tubular member so that it serves as a grease or lubricant container permitting introduction of the lubricant preferably in the form of a suitable grease which is effectively retained and does not require replacement. The main function of the lubricant is to prevent noise and prevent corrosion. The rod 31 arranged within the coiled spring also prevents noise in that it keeps the coils of the spring from interlocking and kinking.

The torsion member for the embodiment of the invention illustrated in Figs. 1 to 6 comprises the annular member 32 slidably embracing the tubular member. The annular member is carried by the arm 34 perforated at 35 to receive an attaching screw. The torsion member is indented to form a lug 36 which coacts with the track 14 while the arm is provided with a lug 37 coacting with the track 15. These lugs are formed by indentations in the parts and are suitably pitched to correspond to the pitch of the tracks. They engage the tracks oppositely, thereby minimizing canting or clutching stresses.

In the embodiment of the invention illustrated in Figs. 7 and 8 the bracket 38 is provided with an eye 39 which engages the projecting end 40 on the bushing 41. In this embodiment the ratchet tensioning means is at the lower end of the fixture.

In the embodiment shown in Figs. 9 and 10 the tubular element 42 has a single spiral track 43 in its outer member 44, the edges of which, shown at 45, are brought into abutting relation. The inner member 46 is coiled to provide a slot receiving the rib resulting from the spiral corrugation forming the track 43. In this embodiment the torsion member 47 is formed integrally with the arm 48, being formed with two lateral extensions at the end of the arm 48 curved to slidably embrace the tubular member and the parts terminating in inturned lugs 49 independently and yieldably engage the opposite edges of the track to facilitate smoothness of action and to reduce noise and chatter.

In the embodiment shown in Figs. 12 and 13 two spiral tracks 50 are formed in the outer member 51 of the tubular element. The torsion member 52 is the same as that shown in Fig. 11 with the exception that it has a second track engaging lug 53 formed in the rear side thereof.

I have illustrated embodiments of my invention which I have found highly practical. I have not attempted to illustrate certain other embodiments and adaptations which I contemplate as it is believed this disclosure will enable those skilled in the art to embody the invention as may be desired.

Having thus described my invention, what I claim as new and desire to secure by Letters Patent is:

1. In a sash balance, the combination of a tubular element having two outwardly facing spiral grooves of the same pitch, said element comprising inner and outer members, each member consisting of a strip spirally coiled with its edges in spaced relation providing a spiral slot, the outer member being in overlying relation to the spiral slot of the inner member and having a spiral rib-like inset therein intermediate its edges disposed in the slot of the inner member and providing one of said grooves, the spiral slot of the outer member being intermediate the edges of the inner member and bottomed thereby and constituting the other of said spiral grooves, a bushing secured within one end of said tubular element provided with ratchet teeth at its inner end, a tension rod disposed within said bushing for rotation therein and provided with a ratchet head coacting with the ratchet teeth of said bushing, an anchoring rod at the other end of said tubular element provided with an attaching bracket and with a bushing fitting within said tubular element, the inner ends of said anchoring and tensioning rods constituting clutch pins, a coiled spring arranged within said element with its ends in clutching engagement within said clutch pins, and a torsion member provided with opposed groove-engaging lugs coacting with both spiral grooves of said tubular element, said tubular element members and said bushing and rods being in lubricant retaining fitting relationship.

2. In a sash balance, the combination of a tubular element having two outwardly facing spiral grooves of the same pitch, said element comprising inner and outer members, each member consisting of a strip spirally coiled with its edges in spaced relation providing a spiral slot, the outer member being in overlying relation to the spiral slot of the inner member and having a spiral rib-like inset therein intermediate its edges disposed in the slot of the inner member and providing one of said grooves, the spiral slot of the outer member being intermediate the edges of the inner member and bottomed thereby and constituting the other of said spiral grooves, a bushing secured within one end of said tubular element provided with ratchet teeth disposed within said bushing for rotation therein and provided with a ratchet head coacting with the ratchet teeth of said bushing, an anchoring member at the other end of said tubular element, a coiled spring arranged within said element with one end connected to said tension member and the other to said anchoring member, and a torsion member provided with opposed groove-engaging lugs coacting with both spiral grooves of said tubular element.

3. In a sash balance, the combination of a tubular element having two outwardly facing spiral grooves of the same pitch, said element comprising inner and outer members, each member consisting of a strip spirally coiled with its edges in spaced relation providing a spiral slot, the outer member being in overlying relation to the spiral slot of the inner member and having a spiral

rib-like inset therein intermediate its edges disposed in the slot of the inner member and providing one of said grooves, the spiral slot of the outer member being intermediate the edges of the inner member and bottomed thereby and constituting the other of said spiral grooves, a tension member mounted on one end of said tubular element, an anchoring member at the other end of said tubular element, a coiled spring arranged within said element with one end operatively connected to said tension member and the other to said anchoring member, and a torsion member provided with groove-engaging lugs coacting with both spiral grooves of said tubular element.

4. In a sash balance, the combination of a tubular element comprising inner and outer members, each consisting of a spirally coiled strip coiled with the edges thereof in spaced relation providing a spiral slot, the outer member overlapping the slot of the inner member and having a spiral corrugation disposed in the spiral slot of the inner member and constituting an outwardly facing spiral groove, the slot of the outer member being underlapped by the inner member, said members being in close fitting lubricant retaining relation to each other, a coiled spring housed within said tubular element and operatively connected thereto at one end, a mounting bracket at the other end of said tubular element and to which said coiled spring is connected, means at the other end of said tubular element for adjusting the tension of said spring from the exterior of said tubular element, and a torsion element comprising an annular torsion member embracing and slidably receiving said tubular element and having an integral offset portion engaging one of said grooves, and an attaching arm provided with laterally spaced slots adjacent the free ends thereof, said annular torsion member having the ends thereof disposed through said slots and folded upon the rear side of said arm, said arm having an inward offset between said slots coacting with the other of said grooves.

5. In a sash balance, the combination of a tubular element comprising inner and outer members, each consisting of a spirally coiled strip coiled with the edges thereof in spaced relation providing a spiral slot, the outer member overlapping the slot of the inner member and having a spiral corrugation disposed in the spiral slot of the inner member and constituting an outwardly facing spiral groove, the slot of the outer member being underlapped by the inner member, said members being in close fitting lubricant retaining relation to each other, a coiled spring housed within said tubular element and operatively connected thereto at one end, a mounting bracket at the other end of said tubular element and to which said coiled spring is connected, means at the other end of said tubular element for adjusting the tension of said spring from the exterior of said tubular element, and a torsion element embracing and slidably receiving said tubular element and having opposed lugs coacting with said grooves.

6. In a sash balance, the combination of a tubular element comprising inner and outer members, each consisting of a spirally coiled strip coiled with the edges thereof in spaced relation providing a spiral slot, the outer member overlapping the slot of the inner member and having a spiral corrugation disposed in the spiral slot of the inner member and constituting an outwardly facing spiral groove, the slot of the outer

member being underlapped by the inner member, a coiled spring housed within said tubular element and operatively connected thereto at one end, a mounting bracket at the other end of said tubular element and to which said coiled spring is connected, and an annular torsion member embracing and slidably receiving said tubular element and provided with an attaching means and with opposed groove engaging lugs coacting with said spiral grooves of said tubular element and adapted to engage the grooves in diametrically opposed relation.

7. In a sash balance, the combination of a tubular element comprising inner and outer members, each consisting of a spirally coiled strip coiled with the edges thereof in spaced relation providing a spiral slot, the strips being in joint breaking relation, the outer of said strips having a spiral groove formed therein providing an inset spiral rib-like part disposed in the slot of the inner member, the slot of the outer member being bottomed by the inner member, a spiral spring housed within said tubular element and connected thereto at one end, an anchoring means for the other end of said spring disposed within said tubular element, said tubular element being adapted to constitute a lubricant chamber in which the spring is enclosed, and means coacting with the tube for torsioning the spring comprising a groove-engaging member embracing and slidably receiving the tubular member and provided with means for attachment and having opposed lugs each adapted to engage one of the grooves of said tubular element at opposite sides of the tubular element.

8. In a sash balance, the combination of a tubular element comprising inner and outer members, each consisting of a spirally coiled strip disposed in joint breaking relation to the other, the outer of said members having a spiral track formed therein, the edges of the convolutions of the outer member being spaced to provide a slot-like track bottomed by the inner member, a spiral spring housed within said tubular element and connected thereto at one end, an anchoring means for the other end of said spring disposed within said tubular element, and means coacting with the tubular element for torsioning the spring comprising a track-engaging member embracing and slidably receiving the tubular member and provided with means for attachment and having means individually engaging one of the tracks of said tubular element.

9. In a sash balance, the combination of a tubular element comprising spirally coiled inner and outer members, the outer member closely embracing the inner member and in joint breaking relation thereto, the outer member having a spiral corrugation constituting a spiral track and having the edges of its convolutions spaced to provide a second spiral track, said members being in close fitting lubricant retaining relation to each other, a coiled spring housed within said tubular element and operatively connected thereto at one end thereof, an anchoring element at the other end of said tubular element and to which the other end of said spring is connected, means for adjusting the tension of said spring from the exterior of said tubular element, and a non-rotatable torsion member slidably engaging said tubular element and provided with track-engaging members coacting with each of said spiral tracks of said tubular element.

10. A tubular element for sash balances adapted to receive a torsion spring and provided with

two groove-like spiral torsion member engaging tracks, each consisting of a spirally coiled strip coiled with the edges thereof in spaced relation providing a spiral slot, the outer member overlapping the slot of the inner member and having a spiral corrugation disposed in the spiral slot of the inner member and constituting an outwardly facing spiral groove, the slot of the outer member being underlapped by the inner member, said members being in close fitting lubricant retaining relation to each other.

11. A tubular element for sash balances having two spiral groove-like torsion member engaging tracks of the same pitch and comprising inner and outer members each consisting of a spirally coiled strip coiled with its edges in spaced relation providing spiral slots, the outer member being in overlying relation to the slot of the inner member and having a spiral rib-like offset therein intermediate its edges disposed in the slot of the inner member and providing one of said spiral groove-like tracks, the spiral slot of the outer of said members being intermediate the edges of the inner member and bottomed thereby and constituting the other of said spiral groove-like tracks, said members being in close engagement to retain lubricant.

12. A tubular element for sash balances comprising inner and outer members, each consisting of a spirally coiled strip coiled with the edges thereof in spaced relation providing a spiral slot, the outer member overlapping the slot of the inner member and having a spiral corrugation disposed in the spiral slot of the inner member and constituting a spiral track, the slot of the outer member constituting a spiral track and being underlapped by the inner member.

13. A tubular element for sash balances having

spiral tracks for coacting with a torsion member and comprising inner and outer members, each consisting of a strip spirally coiled with the edges thereof in spaced relation providing a spiral slot, the strips being in joint breaking relation, the outer of said strips having a spiral track formed therein providing a spiral rib-like part disposed in the slot of the inner member, the slot of the outer member being bottomed by the inner member.

10. 14. A tubular element for sash balances comprising inner and outer members each consisting of a spirally coiled strip, the inner member being coiled with its edges in spaced relation providing a spiral slot, the outer member closely embracing the inner and overlapping the slot thereof and having a spiral corrugation disposed in the spiral slot of the inner member and constituting a spiral track.
15. 15. A tubular element for sash balances having spiral tracks and comprising inner and outer members, each consisting of a spirally coiled strip, the outer member closely embracing the inner and overlapping the joint thereof, the outer member having a plurality of spiral corrugations constituting spiral tracks.
